US0D1003894S

(12) **United States Design Patent** (10) **Patent No.:** **US D1,003,894 S**
(45) **Date of Patent:** **** Nov. 7, 2023**

(54) **COMPUTER NOTEBOOK**

(71) Applicant: **Intel Corporation**, Santa Clara, CA (US)

(72) Inventors: **Jim Okuley**, Portland, OR (US); **Murali Veeramoney**, Portland, OR (US); **Prosenjit Ghosh**, Portland, OR (US); **Denica N Larsen**, Portland, OR (US); **Martin Bone**, Cornwall on Hudson, NY (US); **Gregory Germe**, Oakland, CA (US); **Hong W. Wong**, Portland, OR (US); **Arvind Kumar**, Beaverton, OR (US)

(73) Assignee: **Intel Corporation**, Santa Clara, CA (US)

(**) Term: **15 Years**

(21) Appl. No.: **29/736,505**

(22) Filed: **Jun. 1, 2020**

Related U.S. Application Data

(62) Division of application No. 29/680,695, filed on Feb. 19, 2019, now Pat. No. Des. 888,711, which is a (Continued)

(57) **CLAIM**

The ornamental design for a computer notebook, as shown and described.

DESCRIPTION

FIG. 1 is a perspective view of a computer notebook, showing our new design;

FIG. 2 is a top view of the computer notebook in FIG. 1; FIG. 3 is a bottom view of the computer notebook in FIG. 1;

FIG. 4 is a front view of the computer notebook in FIG. 1; FIG. 5 is a back view of the computer notebook in FIG. 1; FIG. 6 is a side view of the computer notebook in FIG. 1; and, FIG. 7 is another side view of the computer notebook in FIG. 1.

The broken lines shown in the drawings illustrate portions of the computer notebook that form no part of the claimed design.

1 Claim, 3 Drawing Sheets

Related U.S. Application Data

division of application No. 29/650,408, filed on Jun. 6, 2018, now Pat. No. Des. 846,545, which is a division of application No. 29/569,872, filed on Jun. 30, 2016, now Pat. No. Des. 822,658.
